UNITED STATES PATENT OFFICE.

RALPH E. JONES, OF COLUMBUS, GEORGIA.

GAME APPARATUS.

Application filed November 14, 1925. Serial No. 69,051.

This invention relates to a game apparatus, and has for its object to provide, in a manner as hereinafter set forth, an inexpensive and durable apparatus of such class 5 for use in connection with the playing of a new, harmless, beneficial, interesting, athletic, amusing and dexterous game termed "farny".

With the foregoing and other objects in view, the invention consists of the novel construction, combination and arrangement of parts, as hereinafter more specifically described and illustrated in the accompanying drawings, wherein is shown an embodiment 15 of the invention, but it is to be understood that changes, variations and modifications can be resorted to which come within the scope of the claims hereunto appended.

In the drawings wherein like reference characters denote corresponding parts throughout the several views:—

Figure 1 is a top plan view illustrating the arrangement of certain of the elements of the apparatus upon a court.

Figure 2 is an elevation of the score board and the markers used in connection therewith.

Figure 3 is an elevation and Figure 4 a sectional view of the playing period controller or timer.

Figure 5 is an elevation of an arrester.

Figure 6 is a perspective view of one of the receivers.

Figure 7 is an elevation of one of the projectiles.

Figure 8 is a detail of a bearing.

A game apparatus, in accordance with this invention, includes a pair of receivers, a series of dividers, a playing period controller or timer, a back stop, and a score board and which are arranged in a manner as hereinafter referred to upon a court. The apparatus further includes a plurality of globular, projectiles for use by the offense and arresters for the defense.

The game is played by two or four players on what may be termed a "farny" court requiring a minimum space of about 30 by 32 feet, and the court is indicated at 1. At 50 the rear end of the court 1 a back stop 2 of any suitable construction and any suitable height is employed. The dividers, indicated at 3, 4, 5 and 6, are positioned on the court 1, intermediate the ends there-

of. The dividers 3, 5 and 6 extend transversely and are arranged in spaced relation. The divider 4 extends longitudinally of the court and connects the dividers 3, 5 centrally thereof. The dividers preferably are constructed of strips of any suitable material 55 detachably secured in position at the ends thereof. The dividers provide divisional lines upon the court, and in lieu of forming such lines from strips of fabric heavy twine or tape can be employed. The lines 60 may also be formed from stripes of lime.

The divider 3, in connection with the entrance end of the court, forms a playing space 7 for the players acting from an offensive or serving standpoint.

That part of the court between the receivers, each of which is generally indicated by the reference character 8, and the divider 5, provides a playing space 9 for a single defending player, and that part of 70 the court between the dividers 5 and 6 provides a playing space for two defending players.

Preferably the distance between the divider 3 and the entrance end of the court 80 is eight feet; between the dividers 3 and 5, six feet; between the dividers 5 and 6, six feet; between dividers 6 and receivers 8, seven feet, and between the forward end of the receivers and the back stop, five feet. 85

The playing period controller or timer, referred to generally by the reference character 11, is positioned in advance of the divider 3 and at the longitudinal center of the court. The distance is such as not to 90 interfere with an offensive or serving player. The score board, which is indicated generally by the reference character 12, is arranged a substantial distance in advance of the timer.

Each of the receivers 8, which may be termed a basket, consists of a circular hoop 13 supported by two posts 14 and 15 and to which is attached a conical shaped body portion 16, the vertex of the body portion 100 being flexibly and somewhat loosely secured at a suitable height, as at 17 to the backstop 2. The body portion is preferably flexible, and is preferably of canvas or net construction. The hoop is preferably of two 105 parts, an upper half and a lower half. In the preferred construction each half hoop has two openings 17 near each end, with a

longitudinal spacing of several inches. The open end of the canvas is hemmed as at 18, with two liberal openings 19 to the hem, one opposite the other. The half hoops are thus run through the hem and then secured to the posts by means of bolts 20, two bolts at each post, each bolt passing through each of two half hoops. Each hoop is mounted between and in line with its two corresponding posts. The axes of the two hoops are about three feet above the ground, approximately fifteen feet apart, parallel, perpendicular to the line of the back stop, and horizontal or nearly so.

15 The projectiles are in the form of light, inflated balls and one of which is shown in Figure 7 and indicated at 22. The projectiles are approximately seven inches in diameter.

20 The arrester or net, which is employed by each defending player consists of a cone-shaped body portion 23 of foraminous material and open at its forward end. The body portion is connected at its forward end 25 to a hoop 24, which has extending therefrom a handle member 25. The smaller end of the body portion 23 is detachably connected by a snap hook 26 to a wrist band 27, which is secured to the wrist of the defending player.

25 The playing period controller or timer 11 comprises a base 28 having secured to the top thereof a metallic cup 29, and fixedly secured to the base 28 and extending up through the cup 29, axially thereof, as well as projecting a substantial distance thereabove, is a standard 30 having a reduced upper terminal portion 31 about which is eccentrically mounted for revolution a 35 counterbalanced timer tube 32.

30 The tube 32 is formed at one side of its vertical median with a pair of opposed opening slots 33, into each of which there is securely attached by riveting a bearing means 45 in the form of an eyelet. The lower of these 35 is circular and fits loosely about the reduced terminal portion 31. The upper bearing surface or collar 34 is oblong in shape the longitudinal axis being parallel to the 50 axis of the tube. The longitudinal slot in this eyelet or bearing surface permits the tube to be rotated within a limited degree in a manner such that an end of the tube may be moved up and down. The bearing member 35 rests and turns upon the shoulder 36. The end of the tube 32 which is nearer the center of rotation is closed by a counter-weight plug 37. Near the other end, which is of closed construction, there is in the top part of the tube an inlet opening 38 for a spherical member 39, the function of which is to drop through the outlet 40 and strike the cup shaped member 29. This outlet 40 is in the lower part of the tube 32 and near the center of rotation. An

upstanding deflector 41 is within the tube and partly overhangs the outlet 40. The reduced terminal portion 31 extends all the way through the tube and about three-fourths of the way through the axial hole of 70 a wooden cylindrical block 42 which serves as a brake.

The relation of the bearing surfaces 34, 35 is such that either end of the tube may be higher than the other. The weight of the 75 plug 37, however, is such that that end is normally lower than the other.

70 The score board 12 comprises a vertically disposed rectangular body portion 43 formed with two lengthwise extending spaced rows 80 of sockets 44, 45. The sockets of each row are twenty in number. Every fifth socket of a row is offset, as indicated at 46. The sockets of each row are numbered consecutively one to twenty and indicia for such 85 purpose is indicated at 47 and which consists of numbers from one to twenty. One row of numbers is provided and which is common to both rows of sockets. The sockets are numbered consecutively starting with 90 the bottom socket of each row. Arranged above the rows of sockets 44, 45 is conventional means, as at 48, to designate the purpose of the rows of sockets and as shown such conventional means designates the 95 sockets for the recording of the points. One row of sockets is used by a serving or offensive player to mark the scores made, and the other row of sockets is employed for the same purpose by the defensive player. 100 Markers in the form of headed pegs are employed for insertion into the sockets, the markers for one row being red and the markers for the other row being blue. The form of markers is indicated at 49. Sockets 50 for 105 the reception of the markers, when not used, are arranged at the lower part of the body portion. The body portion 43 is furthermore provided with two rows of consecutively 110 designated sockets for indicating the number of innings played and with which associate markers. The rows of sockets are indicated at 51, 52, and every fifth socket is offset, as at 53.

115 The body portion 43 is furthermore provided with two rows of consecutively designated rows of sockets 54, 58, for scoring the number of games played, and every fifth socket of each of said rows is offset, as at 59. The body portion 43 is also provided with means, as at 60, for indicating the 120 number of balls played. As shown, the lower part of the body portion is provided with means for storing three pairs of red markers and three pairs of blue markers. Associated with the means for indicating the 125 number of balls played is a marker 61 which is white.

120 The divider 4 enables defensive players to know where they are standing with ref-

ference to the baskets 8 without turning the head toward the baskets.

The playing period controller or timer 11 controls the period for serving by the offense, and in this connection it will be stated that the ball 39 is dropped in the tube 32 and the latter is spun by the player, or if desired by a timer official by giving the tube a whirl preferably from that end provided with the opening 38. The centrifugal force produced by whirling the tube with the ball in the end balances the tube and when the tube stops spinning the weight 37 will shift the tube to the inclined position shown in Figure 4, causing the short end of the tube to lower, thus elevating the long end and causing the ball 39 to roll in a direction towards the reduced portion 31, and as the ball 39 moves in such direction, it will engage the deflector 41 and the latter will direct the ball through the opening 40 into the member 29, and the contact of the ball with said member will produce a ringing sound or signal.

25 The following tentative general description and rules will give an understanding as to how the game may be played:

General description of the game and general rules.

Purposes: The serving side tries to throw balls into the baskets. When the balls are thrown, the defending side tries to catch them in the hand nets. The timer measures the available time during which the serving side may throw.

Sinking: A ball is sunk when it is thrown by a server and enters directly, or by bouncing, into the basket through the ring thereof. A ball which enters and rolls out counts as sunk. A ball which strikes the basket ring and bounces from the basket is not sunk. It makes no difference how many times, or from what, the ball bounces en route to the basket from the hand of the server.

Netting: A ball, having been thrown or dropped by a serving player, is netted when it is securely caught in a net by a defending player. It cannot be netted after it has touched the body of a defender, a basket, a part supporting a basket, or the backstop, or if it has passed the line of the baskets.

Period: A period begins when a serving player spins the timer. It ends when the timing ball drops, or under other circumstances to be hereinafter referred to. During a period, in singles, not more than one ball is thrown; in doubles, not more than two.

Half: A half is one half of an inning and consists of not more than four periods. Each half includes no more and no less than four scores or penalties. There are usually four balls thrown in a half inning.

Inning: An inning consists of two halves during which each side serves a half. The first halves of innings are served by alternate sides during a match.

Game: Game consists in winning not less than three innings and not less than two innings more than the opposite side has won.

Match: A match consists of a number of games, dependent upon previous agreement. Whichever side first wins the specified number of games wins the match.

Scoring and recording: The score within the inning is recorded on the scoreboard and announced just before the timer is spun at the beginning of each period. Scoring is done by a serving player or by an official. When an inning or a game is won, it is recorded on the scoreboard. Except as otherwise provided, each ball sunk counts five points for the serving side. Except as otherwise provided, each ball netted counts two points for the defending side. Except as otherwise provided, each served ball, neither sunk nor netted, counts one point for the defending side. The score is cumulative during each inning. The side making the highest number of points during an inning wins the inning.

Fouls: A time foul is committed when a serving player throws a ball before the timer has been spun or after the timing ball has dropped. A line foul is committed when a player, during a period, touches the ground with his net frame or body on the wrong side of his limiting lines. A player or official noticing a foul committed by himself or another player will call "foul". The play of that period will cease immediately. No score will be counted for any points won in a fouled period. If only one side has fouled, the penalty will be credited to the score of the opposing side in place of one played ball. If both sides have fouled, no penalty will be counted, and the period will be played over.

Penalties: The penalty for a line foul is five points. The penalty for a time foul is two points. If two or more fouls are committed by one side during one period, the foul committed first determines the amount of the penalty.

If, during a period, a serving player inadvertently drops his ball and it rolls outside the area of the server, it counts as a throw. A defending player may net such a ball, even though it may have come to rest, provided he does so without fouling before the dropping of the timing ball.

At any time in the second half of an inning, if it is apparent that one side is so far behind that there is no possibility of winning or tying the inning, or, if the serving side can win the inning by rolling the remaining balls barely across the divider or line 3, the inning is credited as having been

won accordingly, and the remaining balls are not thrown. However, should the serving side overlook such a situation and unnecessarily throw a ball, losing two or more points thereby, the loss is counted as valid.

A flip of a coin is a suitable method of determining which side shall serve first at the beginning of a match.

10 *Singles.*

In singles, there is one server and one defender. Two baskets are used, but only one net and one ball.

15 The server must play behind divider or line 3. The defender may play anywhere between divider or line 5 and the baskets.

20 The defender being in his proper part of the court and ready with net in hand, the server, with the ball in one hand, spins the timer with the other. He then endeavors to throw the ball into one of the baskets before the timing ball drops. A period terminates in singles, when the timing ball drops, when a foul has been committed, when a ball has 25 been sunk or netted, or when a thrown ball has reached a point such that the defender can have no further opportunity to net it.

Doubles.

20 In doubles there are two players of one side opposed by two players of the other side. Two baskets, two nets and two balls are used.

25 The serving players must play behind divider or line 3 and the defending players must play in the area between dividers or lines 5 and 6.

30 The two serving players or the two defending players may mutually exchange places at any time that they please.

35 When the timer is spun, each defending player should be in position with a net in hand and each serving player should have a ball in hand. Either serving player may spin the timer. Either may throw the ball, or both may throw, either simultaneously or successively at either basket. If desired, after one ball has been played, the other ball may be passed to the player that threw the 40 first and he may throw the second also.

45 Either one or two balls are thrown during a period. Within a period, a serving player is not permitted to pick up a ball already thrown or a third ball.

50 A defending player may remove a ball from his net as soon as he pleases after the ball has obviously been securely netted. During a period, he may net a second ball with or without having removed the first.

55 A period terminates, in doubles, when the timing ball drops, when a foul has been committed, when two balls have been disposed of in play (that is to say, have been sunk, netted or have reached points such that 60 the defenders can have no further oppor-

tunity to net them), or when, one ball having been disposed of, a serving player, waiving the privilege of his side to dispose of the second ball, announces "farny". If a ball is thrown after the announcement of "farny", such ball shall count for nothing.

65 In doubles, a half consists of either two, three or four periods, and there are thrown a total of four or five balls. In each period it is the right of the servers to throw two 70 balls if they so desire, even though there have already been thrown three balls in that half, providing, of course, that the throwing is done within the limit established by the timer.

75 One ball having been thrown, a defending player may by saying "farny" with an inflection of inquiry, suggest to the serving side that the privilege of delivering the second ball be waived. Whether suggested by the 80 defenders or not, a serving player may, under such circumstances, announce "farny" and thus end the period, or the serving player may decline to announce "farny" and in such case if the timing ball drops after 85 one ball has been thrown, the result is the same as though the serving side has announced "farny".

90 When two balls have been thrown in a period, and the total number of balls thrown in the half does not exceed four, both balls count in the scoring. When, however, a period starts with three balls already having been thrown since the beginning of the half, if two more balls are thrown, the more favorable score for the servers is the one counted, excepting, of course, in the event of a foul. At the termination of a period, if 95 four balls have been thrown, the half is ended.

100 105 What I claim is:—

110 115 1. A game apparatus comprising a plurality of dividers for dividing a playing field into and controlling the playing spaces for offense and defense, projectiles in the form of globular elements for the offense, spaced stationary receivers for the projectiles to complete the offensive movement and arranged solely at the rear of the playing space for the defense, and portable arresters 120 to interrupt the offensive action and including flexible means to receive and hold the projectiles to prevent these latter entering the receivers.

125 130 2. A game apparatus comprising a plurality of dividers for dividing a playing field into and controlling the playing spaces for offense and defense, a manually whirlable playing period controlling mechanism for an offensive action on the part of a player and including means to provide an audible signal at the expiration of such period, projectiles in the form of globular elements for the offense, and stationary receivers for the projectiles to complete the 135

offensive movement and arranged solely at the rear of the playing space for the defense.

3. A game apparatus comprising a plurality of dividers for dividing a playing field into and controlling the playing spaces for offense and defense, a playing period controlling mechanism for an offensive action on the part of a player and including means to provide an audible signal at the expiration of such period, projectiles in the form of globular elements for the offense, spaced stationary receivers for the projectiles to complete the offensive movement and arranged at the rear of the playing space for the defense, and portable arresters to interrupt the offensive action and including flexible means to receive and hold the projectiles to prevent these latter entering the receivers.

20 4. A game apparatus comprising a plurality of dividers for dividing a playing field into and controlling the playing spaces for offense and defense, a manually whirrable playing period controlling mechanism for an offensive action on the part of a player and including means to provide an audible signal at the expiration of such period, projectiles in the form of globular elements for the offense, spaced stationary receivers for the projectiles to complete the offensive movement and arranged rearwardly of the defense, portable arresters to interrupt the offensive action and including means to receive and hold the projectiles to prevent these latter entering the receivers, and a score board provided with means to indicate progress and status of the contest.

40 5. A game apparatus comprising a back stop, a pair of spaced projectile receivers arranged forwardly of and having their rear ends anchored to said back stop, said receivers open at their forward ends, means connected with the forward ends of said receivers for maintaining said ends open and further for supporting the receivers at right angles with respect to the back stop, dividers for controlling the playing space of the players for the offense and for the player or players for the defense, globular projectiles for the players of the offense, a projectile arrester for each player of the defense, and connected to such player, and a playing period controlling mechanism arranged at the playing space for the offense.

55 6. A game apparatus comprising a back stop, a pair of spaced projectile receivers arranged forwardly of and having their rear ends anchored to said back stop, said receivers open at their forward ends, means connected with the forward ends of said receivers for maintaining said ends open and further for supporting the receivers at right angles with respect to the back stop, dividers for controlling the playing space of the player or players for the offense and

for the player or players for the defense, globular projectiles for the players of the offense, a projectile arrester for each player of the defense and connected to such player, a playing period controlling mechanism arranged at the playing space for the offense, and a score board for indicating points, innings, games and projectiles thrown.

7. A game apparatus comprising projectiles in the form of globular elements for the offense, means for receiving the projectiles to complete the offensive movement, means to interrupt the offensive action and to receive and hold a projectile to prevent the latter entering the said receiving means, and a manually whirrable timing device to control the playing period of a player for the offense.

8. A game apparatus comprising means for controlling the playing spaces for offense and defense, projectiles in the form of manually thrown globular elements for the offense, a plurality of stationary spaced receivers for the projectiles to complete the offensive movement and arranged solely at the rear of and above the playing space for the defense, and a portable arrester to interrupt the offensive action and having means for connecting it to the wrist of a player for the defense and further including a handle to be gripped by such player.

9. A game apparatus comprising means for controlling the playing space for offense and defense, projectiles in the form of globular elements for the offense, means for receiving the projectiles to complete the offensive movement and arranged solely at the rear of the defense, and a portable arrester to interrupt the offensive action and including means for flexibly connecting it to the wrist of a player for the defense and further including a handle to be gripped by said player.

10. A game apparatus comprising projectiles in the form of globular elements for the offense, means for receiving the projectiles to complete the offensive movement, an arrester to interrupt the offensive action and including means to receive and hold the projectiles to prevent these latter entering the said receiving means, and a manually whirrable timing device for controlling the playing period for a player of the offense.

11. A game apparatus comprising projectiles in the form of globular elements for the offense, spaced stationary receivers for the projectile to complete the offensive movement, a band for connection to the wrist of a defensive player, and an arrester for a defensive player including a handle carrying a projectile receiving net flexibly connected to said band.

12. A game apparatus comprising projectiles in the form of globular elements for the offense, spaced stationary receivers for

the projectiles to complete the offensive movement, a band for connection to the wrist of a defensive player, a projectile arrester for a defensive player including a handle carrying a projectile receiving means flexibly connected to said band, and a playing period controlling mechanism for an offense player.

13. A game apparatus comprising means for separating an offensive player's playing space from a defensive player's playing space, manually thrown projectiles for the offense, means suspended above the defensive player's playing space at the rear thereof for receiving the manually thrown projectiles to complete the offensive movement, and means carried by and having means for connection to a defensive player for arresting, receiving and holding the thrown projectiles to prevent the same entering the said suspended receiving means.

14. A game apparatus comprising means for separating an offensive player's playing space from a defensive player's playing space, manually thrown projectiles for the offense, means suspended above the defensive player's playing space at the rear thereof for receiving the manually thrown projectiles to complete the offensive movement, means carried by and having means for connection to a defensive player for arresting, receiving and holding the thrown projectiles to prevent the same entering the said suspended receiving means, and a manually

whirlable timing device for controlling the playing period for a player of the offense.

15. A game apparatus comprising manually thrown projectiles for the offense, suspended receiving means for said manually thrown projectiles to complete the offensive movement, and a manually carried offensive action arrester element for receiving and holding the manually thrown projectiles to prevent the same entering said suspended receiving means and including a flexibly connected projectile receiving receptacle.

16. A game apparatus comprising means for separating an offensive player's playing space from a defensive player's playing space, manually thrown projectiles for the offense, means suspended above the defensive player's playing space at the rear thereof for receiving the manually thrown projectiles to complete the offensive movement, means carried by and having means for connection to a defensive player for arresting, receiving and holding the thrown projectiles to prevent the same entering the said suspended receiving means, and an audible signal operating means arranged at the offensive playing space and operated by an offensive player for limiting the playing period of such player from the time of operation of said means until the signal is sounded thereby.

In testimony whereof, I affix my signature hereto.

RALPH E. JONES.
